CLAIM

The ornamental design for a cart handle safety cover, as shown and described.

DESCRIPTION

FIG. 1 is a perspective top front right view of a cart handle safety cover, showing my new design;

FIG. 2 is a perspective top rear left view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left elevation view thereof; and,

FIG. 8 is a right elevation view thereof.
